UNITED STATES PATENT OFFICE.

WILLIAM EDWARD PRESCOTT, OF LONDON, ENGLAND, ASSIGNOR TO BAKER-PERKINS COMPANY INCORPORATED, OF WHITE PLAINS, NEW YORK.

STOP-MOTION APPARATUS FOR USE IN MACHINES EMPLOYING CONVEYED TRAYS OR EQUIVALENTS.

Application filed October 12, 1923, Serial No. 668,219, and in Great Britain October 27, 1922.

This invention relates to apparatus or machines in which trays or the like carrying various articles or materials are carried along on conveyers, for example of the endless chain variety, provided with abutments or equivalents which engage the trays and forward them along with the conveyer. An example of such an apparatus to which the present invention is especially applicable is

10 one used in the confectionery industry in which the trays contain starch or like powdered material used to provide moulds for receiving material constituting "centres" for sweetmeats, said trays being caused to pass under a device by which the starch is levelled and superfluous material strickled off.

15 A disadvantage of machines of this character is that the trays frequently have the tendency to partially lift off the conveyer and tilt or ride upwards, or sometimes over one another and the object of the invention is to provide means whereby on such lifting or riding occurring the machine will be immediately stopped automatically.

20 For this purpose the levelling device or some similar member under which the trays are caused to pass and with which they will lightly or frictionally engage on their passage thereunder whilst on the conveyer, is

25 mounted in such a manner that it will lightly rest on the trays by gravity for example by being suspended from a suitable support by links so that should a tray lift, rise or assume an angular position on the conveyer

30 the levelling or similar device will also be swung on its suspension and be caused to rise also. This rising movement of the levelling device will, in one embodiment of the invention, impart movement to a member suitably in the form of a rod having at one end a roller bearing on said device and at the other end adapted to actuate a switch to break a circuit, and stop the machine if

35 electrically driven for example through a rheostat or other suitable arrangement. The switch operating member may be provided with means for adjusting its effective length for proper operation of the switch under varying conditions.

40 Instead of electrical means being used for controlling the stopping of the machine in another embodiment this may be effected mechanically throughout for example, by

coupling what has been termed the switch operating member to a lever or rod system 55 which will release a catch or equivalent and allow spring means or the like to throw over a belt fork, operate a clutch or actuate or release some other mechanical motion to stop the machine.

50 Two embodiments of the invention are illustrated in the accompanying drawings, Figs. 1 and 2 showing in sectional diagram electrically operated means in two positions and Figs. 3 and 4 mechanically operated 65 means, Fig. 3 being a sectional end view and Fig. 4 a side elevation.

To first refer to Figs. 1 and 2, *a* designates a conveyer chain as used in the mechanism referred to having raised links or abutments 70 *a*¹ for forwarding the trays, and *b* the trays thereon; *c* designating the levelling or strickling device which as shown is suspended from the framing *c*¹ by links *d* so that on the tray riding up on the chain or becoming inclined the levelling device will also rise as shown in Fig. 2. Bearing on the back of the levelling device *c* is a roller *e* carried by a rod *f* slidable in a sleeve *g* carried by the framing *c*¹ and provided at its 75 upper end with a screw *f*¹ for adjustment purposes. This screw is normally out of contact with the push *g*¹ of any appropriate kind of switch *h* which is connected by the conductors *h*¹ to a coil *h*² forming part of a 80 rheostat *h*³ adapted to control the starting and stopping of the machine to which the invention is applied. In Fig. 1 the switch *h*⁴ of the rheostat is in position for normal operation of the machine, but in Fig. 2 the rod *f* has engaged the push *g*¹ of the switch *h* thus breaking the circuit to release the switch *h*⁴ and cause stoppage of the machine. The switch *h*⁴ is returned to normal 85 as by a suitable spring *h*⁵.

90 In Figs. 3 and 4 *i* designates the tray and *j* the levelling or strickling device carried by links *j*¹ as previously described. Bearing on the upper part of the levelling device is a rod *k* provided at the top with a screw 100 *k*¹ for adjusting purposes. On the tray riding or lifting as above mentioned the levelling device also rises and the rod *k* lifts one arm *l* of a lever, the other arm *l*¹ of which is depressed to disengage a rod *m* under the 105 action of a spring *m*¹ and which is in oper-

2
ative engagement with a bar n adapted to operate a clutch, belt-fork or other appropriate device for stopping the machine. The rod m is provided with a handle m^2 for resetting the spring when it is desired to restart the machine after a stoppage.

The spring m^1 exerts its pressure upon a suitable lug carried by the bar n , and through the medium thereof reciprocates 10 said bar n to operate the means for stopping the machine.

What I claim as my invention and desire to secure by Letters Patent of the United States is:—

15 1. In a stop-motion mechanism for use with machines employing conveyed trays the combination of a levelling device adapted to strickle off the material in said trays

and means for bringing said mechanism into operation when the levelling device rises. 20

2. In a stop-motion mechanism according to claim 1, a roller bearing on the levelling device and carried by a rod adapted to engage and operate a switch electrically connected to a rheostat adapted to control the 25 operation of the machine.

3. In a stop-motion mechanism according to claim 1, a rod bearing on the levelling device and adapted to operate means to release a spring-pressed member in operative connection with a controlling means for the machine. 30

In witness whereof I have signed this specification.

WILLIAM EDWARD PRESCOTT.
